UNITED STATES PATENT OFFICE.

PETER A. COUPAL, OF BOSTON, MASSACHUSETTS, AND CHARLES D. WOOD, OF LINCOLN, RHODE ISLAND, ASSIGNEES TO THE BOOT AND SHOE SOLE LAYING COMPANY, OF PORTLAND, MAINE.

SOLE-LAYING MACHINE.

SPECIFICATION forming part of Letters Patent No. 335,016, dated January 26, 1886.

Application filed June 8, 1885. Serial No. 168,058. (No model.)

To all whom it may concern:

Be it known that we, PETER A. COUPAL, of Boston, in the county of Suffolk and State of Massachusetts, and CHARLES D. WOOD, of Lincoln, in the State of Rhode Island, have invented certain new and useful Improvements in Sole-Laying Machines, of which the following is a specification.

This invention relates to that class of machines for pressing cement-coated soles against lasted boot or shoe uppers, in which the last holding the upper is rigidly supported and the cement-coated sole is pressed against the lasted upper by an elastic bed, which is movable toward and from the rigidly supported last, and is moved toward the last by mechanism controlled by the operator.

The invention consists in certain improvements in the construction of the sole-supporting bed and in the means employed for adjusting said bed toward and from the last, as we will now proceed to describe and claim.

Of the accompanying drawings, forming a part of this specification, Figure 1 represents a front elevation of an improved machine. Fig. 2 represents a side elevation of the same. Fig. 3 represents a vertical section on line xx , Fig. 1. Fig. 4 represents a perspective view of a part of the machine.

The same letters of reference indicate the same parts in all the figures.

In the drawings, a represents the last-supporting jack, which is composed of two standards, 23, one having a spindle at its lower end adapted to be engaged with the spindle-socket in the heel portion of the last, and the other a toe-rest. Said standards are adapted to slide toward and from each other on the head, and have tapped sockets which receive a right and left hand threaded screw-rod, b , journaled at its center in a bearing in the head c , the rotation of said rod moving the standards 23 simultaneously toward and from each other and adapting them to different-sized lasts.

e represents the supporting portion of the frame, from which rise two vertical standards, ff , supporting the head c .

g represents the support for the cement-coated outer soles. Said support is composed

of a metallic block or holder, 4, having trunnions 55 projecting from its opposite sides, a bed, 6, of yielding rubber, supported by said block and having its central portion made thickest, as shown in Fig. 3, and two spring-supported metal plates, 77, under the thinner portions of the bed 6, the springs 8, supporting said plates, being applied to studs bearing against the plates, the springs being partially contained in sockets in said block. The trunnions 55 are journaled in sockets in a cross-head, i , which is adapted to slide vertically on the standards ff , and is operated by mechanism, hereinafter described. The block 4 is therefore adapted to oscillate so as to permit the bed to adapt itself to the longitudinal inclination of the bottom of the last.

k represents a rock-shaft journaled in lugs ll on the cross-head i , and provided with a lever or handle, m , and with short arms nn , projecting backwardly, the rock-shaft, arms, and lever being rigidly connected.

o represents a treadle-lever pivoted at p to a fixed support, and having an arm p' .

q represents an arm or link pivoted at one end to the arm p' and at the other end to the arm n . The arm p' and link q constitute a toggle-joint, while said link and the arms nn constitute another toggle-joint.

When the machine is to be operated, the lever m is raised by the operator until the arms nn are brought approximately into line with the link q , thus partially raising the cross-head i , block 4, and bed 6, and bringing the bed into the desired proximity to the bottom of the last. The parts are held in this position by the engagement of a spring-dog, r , on the lever m , with a segmental ratchet-bar, s , which is pivoted to the link q . The operator then places the cement-coated sole upon the bed 6, and by depressing the treadle-lever throws the arm p' and link q into alignment, or approximately so, and thus gives the bed an additional upward movement and presses the sole with the required firmness against the lasted upper, the pressure being retained as long as desired by engaging the treadle-lever with a notched holding-standard, u . When the pressure has been sufficiently continued for the cement to "set" the operator disen-

gages the lever m from the ratchet-bar s , and depresses said lever until a stop or projection, v , thereon abuts against a similar stop, v' , on the link q , the cross-head with the block and bed being thus allowed to descend. The treadle o is also released, so that the arm p' and link q may be set for their next action, or, in other words, assume the position shown in Figs. 2 and 3.

10. It will be observed that the rock-shaft k , lever m , and arms n give the block 4 and bed 6 a greater extent of vertical movement than is afforded by the pressure devices consisting of the treadle-lever o , its arm p' , and the link q , thus enabling the bed to be sufficiently separated from the bottom of the last to permit the easy removal of a boot or shoe therefrom after the attachment of each sole, while the ratchet-bar s and dog r enable the bed to be held at any desired height while the operator is applying the sole to the bed.

It is desirable that the bed be brought as close as possible to the bottom of the last before the sole is placed on it, and as the last-bottoms often vary in height the ratchet and dog enable the bed to be supported at any desired height prior to the final pressing operation, the increased thickness of the rubber bed 6 midway between its ends enables it to conform to the curvature of the shank cross-wise of the last more perfectly than it could if the rubber had been the same thickness at the center as at the ends, while the thinner end portions and the independent metal plates and supporting-springs enable the end portions of the bed to accommodate themselves

to variations in the curvature of the last at the toe and heel. We do not limit ourselves, however, to the construction of the bed.

We do not claim anything shown in Patent 40 No. 315,923, for sole-laying machine granted to A. Epple, Jr., April 14, 1885, but have improved upon the construction shown in said patent by the addition of the ratchet-bar s and dog r , and by the described peculiarities 45 of the sole-support.

We claim—

1. The combination, with the movable bed and its supporting devices, including the sliding cross-head, of the rock-shaft pivoted to 50 said cross-head and provided with the lever m and arms n , the link q , pivoted to the arms n , the treadle-lever having an arm, p' , pivoted to the link q , the ratchet-bar s , pivoted to the link, and the dog r on the lever m , adapted to 55 engage with said ratchet-bar, as set forth.

2. The sole-support composed of the supporting-block, the rubber bed 6, having the thickened central portion bearing on the block and reduced ends, and the spring-supported 60 plates interposed between the reduced portion of the rubber bed and the block, as set forth.

In testimony whereof we have signed our names to this specification, in the presence of two subscribing witnesses, this 5th day of 65 June, 1885.

PETER A. COUPAL.
CHARLES D. WOOD.
